UNITED STATES PATENT OFFICE.

OWEN E. McMAHON, OF ELGIN, ILLINOIS.

REEL.

No. 879,570.

Specification of Letters Patent.

Patented Feb. 18, 1908.

Application filed April 23, 1907. Serial No. 369,859.

To all whom it may concern:

Be it known that I, OWEN E. McMAHON, a citizen of the United States, and a resident of Elgin, in the county of Kane and State of Illinois, have invented certain new and useful improvements in Reels; and I do hereby declare that the following is a full, clear, and exact description thereof, reference being had to the accompanying drawings, and to the letters of reference marked thereon, which form a part of this specification.

This invention relates to improvements in wire reels designed to support a coil of wire in position for the wire to be unwound therefrom and the invention consists in the matters hereinafter set forth and more particularly pointed out in the appended claims.

As shown in the drawings:—Figure 1 is a top plan view of a reel embodying my invention. Fig. 2 is an axial section, taken on line 2—2 of Fig. 1. Fig. 3 is a fragmentary horizontal plan view of the coil platform or support. Fig. 4 is a detail, taken on line 4—4 of Fig. 3. Fig. 5 is a plan view of a locking ring on the reel frame constituting part of the means by which the coil confining ring is locked in place. Figs. 6 and 7 are details illustrating the manner of locking said coil confining ring. Fig. 8 is a section, taken on line 8—8 of Fig. 2.

As shown in the drawings, A designates a stationary support upon which the reel is rotatively mounted. The reel comprises, in general terms, a horizontal coil supporting platform, designated as a whole by B, a coil confining ring C which engages the upper side of the coil to hold the same on the platform, standards D rising from the platform and carrying at their upper ends a locking ring E, and a ring C' overlying and removably secured upon the locking ring E and supporting the confining ring C through the medium of radial arms C'', which latter are riveted or otherwise suitably attached at their ends to the inner and outer rings C' C. The reel frame is rotatively mounted on a vertical shaft F which is headed at its lower end and is fixed to the base-plate A by means of a clamping plate A', as shown in Fig. 2. The coil supporting platform is not a continuous platform as herein shown, but comprises radial angularly separated members composed of two pairs of bars B' B' of angle-bar cross-section, which cross each other and are secured together at the center of the reel frame. The said supporting or platform

bars are connected at their outer ends by means of a ring B' also of angle bar cross-section. They are carried at the center of the frame by a bearing sleeve G surrounding 60 and rotating upon the shaft F. The said bearing sleeve G is provided with a base-flange G' which rests upon the plate A', as shown in Fig. 2.

The manner of attaching the platform or 65 supporting bars B' to said bearing sleeve is shown most clearly in Figs. 2, 3 and 4 and is made as follows: The said bearing sleeve is rectangular in cross-section and the vertical flanges of said bars bear laterally against the 70 flat faces of said sleeve and rest at their lower margins on the base flange of the sleeve. The horizontal webs of one pair of the bars rest on the horizontal webs of the other pair of said bars. Said bars are secured together and to the base-flange of the sleeve by means of bolts b b extending through the overlying webs of said bars and through openings in the base-flange G' of 75 said sleeve. The heads at the lower ends of 80 said bolts occupy countersunk recesses in the lower face of said flange.

The standards D which support the locking ring E of the frame each comprises two converging members or legs d d' and is made 85 of a single piece of bar iron bent between its ends to the proper form. They are attached at their lower ends to the webs of said platform bars and to short plates d' extending across and attached to said webs. The said standards are formed at their upper ends with horizontal seats for the locking ring E, which latter is attached thereto by bolts d''. The coil confining ring C and its supporting frame, consisting of the ring C' and the radial 90 connecting arms C'', are removably mounted in said frame whereby it may be removed therefrom when a coil of wire is placed on the reel, and it is thereafter locked to the frame in a manner to bear upon the upper side of 100 the coil to confine the coil in place. The means for thus removably locking said confining ring in place will be understood from a consideration of Figs. 1, 2, 5, 6 and 7. The said locking ring is provided on its inner 105 margins with a plurality of angularly separated notches e, equal in number to the radial arms C'' of the coil confining ring frame. The said arms C'' are extended inwardly beyond the inner margin of the ring C' and 110 are shaped to provide, radially inside said ring, hooks c that are adapted to extend

beneath the inner margin of the locking ring. The said arms and hooks are so spaced as to pass through the notches *e* of the locking ring when the confining ring is applied to the reel and, by rotating said ring and its frame to a short angular extent, the hooks *e* are shifted out of line with said notches and beneath the solid part of said ring thereby locking said parts firmly in place. As herein shown, the inner margin of the locking ring is provided adjacent to said notches *e* with stops *e*¹ that limit the extent of angular movement by the confining ring to adjust the same to place.

In order to adjust the reel to coils of wire of varying diameters the supports against which the inner side of the coil bears are adjustable radially inwardly and outwardly and are arranged to be locked in any adjusted position. The said supports for the inner side of the coil comprise swinging levers *H* *H* which are hinged at their lower ends to pins or bolts *h* extending between the platform bars *B*² and are adapted to swing at their upper ends towards and from the center of the reel. The upper ends of said levers are located inside the coil confining ring *C* and extend above said ring. As herein shown four of said levers are employed, one hinged between the outer ends of each pair of supporting or platform bars *B*¹. The means for adjusting said levers inwardly and outwardly and locking them in adjusted positions comprise links *H*¹ *H*² that are pivoted at their outer ends to lugs *h*¹ located centrally of the levers and at their inner ends to adjusting screws *h*² that extend through and have sliding engagement with slots *d*¹ formed in the inner members *d* of the standards *D*. Nuts *h*³ engaging the screw-threaded inner ends of said adjusting bolts serve to lock said bolts in adjusted positions. When the standards *D* are made of the form herein shown, the outer members *d* thereof are slotted to permit the links of the adjusting bars to pass therethrough, as shown in Figs. 1 and 2. By releasing the nuts *h*³ and sliding the adjusting bolts upwardly and downwardly on the inner members of said standards, the levers *H* may be swung inwardly or outwardly to positions desired and locked in such adjusted positions. As a further and separate improvement the said adjusting levers are provided at their upper ends with loops or handles *H*², whereby the reel as a whole may be conveniently carried from place to place.

A friction brake is applied to the rotating bearing sleeve *G* in such manner as to place more or less of a drag on the rotation of the reel and thereby enabling a proper tension to be maintained on the wire as it is unwound from the reel. The friction device herein shown is made as follows: The shaft *F* is provided with a vertical, longitudinal slot

through which extend upper and lower horizontal cross-bars *f*¹ *f*² between which is interposed a spiral expansively acting spring *f*³ that surrounds said shaft. The lower cross-bar *f*² rests on a friction washer *f*⁴ which in turn rests on the top or end face of the bearing sleeve. *F*¹ designates an adjusting screw which has screw-threaded engagement with an axial hole in the upper end of the shaft *F* and bears at its lower end against the upper cross-bar *f*¹. Said adjusting screw is provided with a hand wheel *f*⁵. By turning down said adjusting screw more or less pressure is applied through the spring *f*³ to the friction washer thereby forcing the same into yielding friction contact with the upper end of the bearing sleeve with the effect of producing the braking or retarding action desired.

I claim as my invention:—

1. A reel comprising a rotative platform or support, a coil confining device above said support, between which and the support is adapted to be confined a coil of wire, said confining device comprising a ring and radial arms extending inwardly therefrom for attachment to the reel frame.

2. A reel comprising a rotative platform or support, a coil confining ring located above said support, between which and the support is adapted to be confined a coil, and means for locking said confining ring to the reel frame constructed to lock and release said ring by relative rotation of said ring and the part to which it is removably fixed.

3. A reel comprising a rotative platform or support, a coil confining ring located above said support, between which and the support is adapted to be confined a coil, and means for locking said confining ring to the reel frame comprising a locking ring on the reel frame, and arms extending inwardly from said confining ring and adapted to releasably engage said locking ring.

4. A reel comprising a rotative platform or support, standards rising therefrom, a locking ring supported on said standards, and a coil confining device removably connected with said locking ring between which and the platform is adapted to be confined a coil of wire.

5. The combination with a rotative coil support or platform of a reel, of standards rising therefrom, a locking ring supported on said standards and provided at its inner margins with notches, a confining ring provided with radial, inwardly extending arms provided with hooks adapted to pass through said notches and by angular movement of the confining ring to be engaged with the unnotched portion of the inner margin of the ring.

6. In a reel, the combination with a rotative platform or support, of a notched locking ring, a confining ring provided with

radial supporting arms having at their inner ends hooks adapted to engage said notched locking ring, and a ring connecting the inner ends of said arms.

5 7. A reel comprising a horizontal, rotative platform, standards rising from and attached to the platform, levers pivoted to the platform to swing toward and from the center of the reel for sustaining the inner side of a 10 coil of wire, and adjusting devices carried by said standards for adjusting the levers toward and from the center of the reel.

15 8. A reel comprising a horizontal, rotative platform, standards rising from and attached to the platform, levers pivoted to the platform to swing toward and from the center of the reel sustaining the inner side of a coil of wire, and adjusting devices carried by said standards for adjusting the levers toward 20 and from the center of the reel comprising links pivoted at their outer ends to said levers, and clamping devices having adjustable connection with said standards to which the inner ends of the links are pivoted.

25 9. A reel comprising a horizontal, rotative

platform or support, levers pivoted to said support to swing towards and from the center of the reel for sustaining the inner side of a coil of wire, and means for adjusting said levers toward and from the center of the reel, 30 said levers being formed at their upper ends to provide handles.

10. A reel comprising a horizontal, rotative support, a vertical standard about which said support rotates, a bearing sleeve 35 rotating on said standards, means for confining a coil of wire thereon, said support comprising bars arranged in crosswise relation and attached to each other and said bearing sleeve of the center of the reel, and 40 a ring surrounding and fixed to the outer ends of said bars.

In testimony, that I claim the foregoing as my invention I affix my signature in the presence of two witnesses, this 23rd day of 45 March A. D. 1907.

OWEN E. McMAHON.
